COMBINED REFLECTOR AND LENS

Sidney A. Heenan, Park Ridge, and Eugene A. Peterson, Northbrook, Ill., assignors to Amerace Esne Corporation, Union, N.J.

Filed Dec. 29, 1969, Ser. No. 20,688

Term of patent 14 years

Int. Cl. D29—99; D12—99; D26—06
U.S. Cl. D72—1

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 1 is a front elevational view of a combined reflector and lens incorporating our new design;

FIG. 2 is a cross-sectional view taken on line 2-2 of FIG. 1;

FIG. 3 is a cross-sectional view taken on line 3-3 of FIG. 1;

FIG. 4 is a front elevational view of a second embodiment of our design;

FIG. 5 is a cross-sectional view taken on line 5-5 of FIG. 4;

FIG. 6 is a cross-sectional view taken on line 6-6 of FIG. 4;

FIG. 7 is a front elevational view of a third embodiment of our design;

FIG. 8 is a cross-sectional view taken on line 8-8 of FIG. 7;

FIG. 9 is a cross-sectional view taken on line 9-9 of FIG. 7;

FIG. 10 is a front elevational view of a fourth embodiment of our design;

FIG. 11 is a cross-sectional view taken on line 11-11 of FIG. 10; and

FIG. 12 is a cross-sectional view taken on line 12-12 of FIG. 10.

We claim:

The ornamental design for a combined reflector and lens, substantially as shown and described.
